Des. 233,587
Patented Nov. 12, 1974

233,587

SCISSORS

Italo Marco Laurenti, 8200 Kennedy Blvd. E.,
North Bergen, N.J. 07047

Filed Jan. 28, 1974, Ser. No. 436,855

Term of patent 14 years

Int. Cl. D8—03

U.S. Cl. D8—57

FIG.1

FIG.2

FIG.3

FIG.4

FIG.5

FIG. 1 is a top plan view of scissors showing my new design;

FIG. 2 is a side elevational view thereof;

FIG. 3 is a bottom plan view;

FIG. 4 is a blade end elevational view; and

FIG. 5 is a handle end elevational view.

I claim:

The ornamental design for scissors, substantially as shown and described.
